UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING MACHINE.

Application filed September 18, 1918. Serial No. 324,288.

To all whom it may concern:

Be it known that I, JOHN KIEWICZ, a citizen of the United States, residing at Boston, county of Suffolk, State of Massachusetts, have invented an Improvement in Sewing Machines, of which the following description, in connection with the accompanying drawing, is a specification, like characters on the drawing representing like parts.

10 This invention relates to sewing machines and particularly to buttonhole sewing machines of that type which are equipped with a thread-trimming mechanism carried by the work-holding means and arranged to cut the 15 thread between the work and the work-holding means at the end of a stitching operation on a buttonhole.

The object of the invention is to provide an improved thread-trimming device which 20 is simple in construction and accurate in operation and which will cut the thread close to the work.

In order to give an understanding of my invention, I have illustrated in the drawings a selected embodiment thereof which will now be described, after which the novel features will be pointed out in the appended claims.

Fig. 1 is a side view of a buttonhole sewing machine embodying my invention;

Fig. 2 is a plan view of a portion of the sewing machine including the clamp plate showing my improved thread-trimming device;

35 Fig. 3 is a section on the line 3—3, Fig. 2;

Fig. 4 is an underside view of the bed plate showing the actuator for the thread-trimming device.

Since my invention relates particularly to 40 the thread-trimming means, I have not deemed it necessary to illustrate herein a complete buttonhole sewing machine, but have simply shown in the drawings a sufficient portion of such a machine to enable 45 the invention to be understood.

My invention is herein shown as it might 50 be applied to a buttonhole sewing machine of the well-known "Reece" type, examples of which may be seen in United States Letters 55 Patent No. 1,188,944, dated June 27, 1916, or No. 1,361,871 dated Dec. 14, 1920.

In the sewing machine herein illustrated, 1 60 indicates the bed plate portion of the frame from which rises the head or overhanging 65 arm 2 that carries the upper thread-handling

mechanism herein shown in the form of a reciprocating eye-pointed needle 3 carried by the usual reciprocating needle bar 4.

The upper thread-handling mechanism 60 co-operates with an under thread-handling mechanism of usual type which is carried on a rotatable turret 8 that is mounted for turning movement in the depending portion 9 of the frame, said turret carrying at its upper end the throat-plate 10 which is provided with the aperture 11 through which the upper needle 3 and the needle of the under thread mechanism operate and through which the under thread extends as it passes to the work.

The work which is shown in dotted lines at *w*, Fig. 1, is carried by work-holding means comprising a clamp plate 5 slidably mounted in ways 6 formed in the bed plate 1, and work clamps 7 pivoted to the clamp 75 plate and by which the work is clamped thereagainst. The clamp plate moves back and forth in the ways 6 during the sewing on the buttonhole and is provided with a sewing opening 40 through which the sewing 80 is done. The movement of the clamp plate in the ways 6 is derived from a feed cam 14 as usual in buttonhole sewing machines of this type. These buttonhole sewing machines are usually constructed so that when 85

they are set in operation the work clamps 7 are first clamped against the work *w* thereby clamping the latter to the clamp plate 5 and then the buttonhole cutter, if one is used, is actuated to cut the buttonhole, after which 90 the clamp plate is moved by the cam 14 toward the front of the machine to carry the work from buttonhole-cutting to stitching position. The stitch-forming mechanism is then set in operation and the clamp plate 95 continues its movement first in one direction and then in the other to cause the stitching to be performed down one side of the buttonhole and then back along the other side. When the buttonhole is finished, the stitch-forming mechanism is brought to rest with the needle 3 raised and the work clamps 7 are then released to unclamp the work, after which the clamp plate is given a movement to carry the work from stitching to buttonhole-cutting position. The entire machine 100 is then automatically brought to rest.

My present improvement relates to a novel thread-trimming device which is carried by the clamp plate 5 and is adapted to operate 110

between the work and the clamp plate for cutting the thread at the end of the stitching operation. This thread-trimming device comprises a shearing block or plate 15 secured to the clamp plate 5 and having a shearing edge 16 adjacent one edge of the sewing opening 40, and a co-operating cutting element 17 pivoted to the clamp plate at 18 and provided with a cutting edge 19 situated to pass over the shearing edge 16 when the member 17 is turned about its pivot. Said member 17 is also provided with the convexly-curved edge 20. The member 17 may conveniently be formed of relatively thin sheet metal, so that it will take up comparatively little room in a vertical direction, and it and the shearing block 15 are situated adjacent one end of the sewing opening 40.

The construction is such that at the end of a stitching operation in a buttonhole the parts are in the position shown in Fig. 2, and the cutting member 17 is situated adjacent the throat-plate 10 and in such position that when it is turned into the dotted line position, Fig. 2, the cutting edge 19 will be carried across the throat-plate and the shearing edge 16. During this movement the back 29 of the cutting member engages the threads leading from the under-side of the work, it being understood, of course, that this cutting member is located beneath the work. The threads which are thus depending from the work are the under-thread, the stay-cord, if one is used, and the loop of upper thread which is held by the looper when the stitching mechanism comes to rest. The movement of the cutting member 17 will sever all of these threads close to the work.

The means I have herein provided for actuating the cutting member 17 are such that said member receives its movement immediately after the stitch-forming mechanism has been brought to rest and after the clamps 7 have been raised to unclamp the work, but preferably before the clamp plate is moved from stitching to buttonhole-cutting position. While any suitable means for actuating the cutter 17 may be employed I will preferably use a construction similar to that shown in my above-mentioned co-pending application Ser. No. 269,201. The cutting element 17 is pivotally connected by a connecting rod 21 to a lever 22 pivoted to the clamp plate at 23. Said lever is acted on by a spring 24 which tends to keep it in the position shown, and the cutting element 17 is provided with a stop shoulder 25 adapted to engage a stop 26 carried by the clamp plate. The spring 24 thus normally keeps the disk 17 in the position shown in Fig. 2.

The lever 22 is acted upon at the appropriate time by an actuating lever 27 which extends underneath the frame and is pivot-

ed thereto at 28. The inner end 29 of this lever is adapted to be engaged by a roll 30 carried by an arm 31 which is rigid with the feed cam 14, all as illustrated, in my above-mentioned application. This arm 31 is so positioned that the roll 30 will wipe against and actuate the lever 27 just as the clamp plate has been brought to rest at the end of the stitching operation and the work clamps 7 have been raised, and the turning movement of the lever 27 will cause the outer end 32 thereof to engage the end of the lever 22 and turn the latter into the dotted line position Fig. 2, thereby giving the cutting member 17 its thread-cutting movement. As soon as the roll 30 has wiped past the end 29 of the lever 27, the cutter will be returned to its normal position by the spring 24.

I have shown the shearing block 15 as adjustable transversely of the clamp plate 5, it being held in its adjusted position by screws 33 operating in slots 44 formed in said shearing block. The shearing edge of the shearing block is situated a slight distance to one side of the throat-plate and consequently when the cutting member 17 has its thread-cutting movement the cutting edge 19 will engage the threads leading from the work as said cutting edge is passing over the throat plate and will draw said threads laterally against the shearing edge 16, at which point the threads are severed. A short length of stay-cord will thus be drawn from the source of supply before said cord is cut, and the amount which is thus drawn off or pulled out will depend upon the distance which the shearing edge 16 is located from the throat plate 10. It is desirable that there should be a sufficient length of staycord pulled through the throat plate to enable the stitching on the next buttonhole to be commenced properly, and by adjusting the shearing block 15, the amount of stay-cord which is thus pulled off before the shearing takes place can be regulated. Where a stay-cord clamping device such as shown in United States Letters Patent No. 1,826,869, dated Dec. 30, 1919, is employed in connection with the throat plate 10, then such length of stay cord as has been pulled off by the member 17 before the cord is sheared will be held in proper position for the beginning of the stitching on the next buttonhole.

In order that the cutting operation of the member 17 may be positive, it is important that the cutting edge should have a good shearing action against the shearing edge 16. To provide for this I preferably make the member 17 of resilient material and having a slightly convex shape so that the action of the pivot screw 18 serves to hold the edges of said member in firm engagement with the clamp plate.

34 designates a pull-off lever similar to that mentioned in my above-mentioned co-pending application which is actuated by the lever 27 to pull off a length of under 5 thread before the thread cutter is operated. This pull-off lever 34, however, forms no part of my present invention.

My improved thread cutter is very simple in construction and positive in operation 10 and by means of it the thread will be cut close to the under side of the work.

I claim:

1. In a sewing machine adapted to sew a short seam and then come to rest, the combination 15 with stitch-forming mechanism including a throat-plate, of a clamp plate on which the work is supported, means for moving the clamp plate and stitch-forming mechanism relative to each other, said clamp plate having a shearing edge on its work-receiving face situated at one side of the throat-plate, a cutting member pivotally mounted on the clamp plate and having a cutting edge, turning movement of the cutting member carrying said cutting edge across the throat-plate so that it engages the threads extending therefrom and pulls off a length of thread and then across the shearing edge thereby to sever the thread, and 20 means operative at the end of the stitching operation to actuate said cutting means.

2. In a sewing machine adapted to sew a short seam and then come to rest, the combination 25 with stitch-forming mechanism including a throat-plate, of a clamp plate on which the work is supported, a cam for moving the clamp plate and stitch-forming mechanism relative to each other, said clamp plate having a shearing edge on 30 its work receiving face at one side of the throat-plate, a cutting member pivotally mounted on the clamp plate and having a cutting edge, turning movement of the cutting member carrying the cutting edge across the throat-plate and then across the shearing edge, and means associated with 35 said cam for actuating the cutter at the end of the stitching operation whereby a length of thread is first drawn off by the cutter and then said thread is severed close to the work.

3. In a sewing machine, the combination 40 with stitch-forming mechanism, of a clamp plate on which the work is clamped, said clamp plate having a sewing opening, a shearing block provided with a shearing edge secured to the clamp plate, a cutting member pivoted to the clamp plate and operating to cut the thread between the work and the clamp plate, a cam member for moving the clamp plate relative to the stitch-forming mechanism, and means associated with said cam member and operating independently of the movement of the clamp plate for actuating the cutting member at 45 the end of the stitching operation.

4. In a sewing machine, the combination 50 with a clamp plate on which the work is supported and which is provided with a sewing opening, of stitch-forming mechanism including a throat-plate situated beneath the sewing opening, means for moving the clamp plate and stitch-forming mechanism relative to each other, said clamp plate having a shearing edge at one side of the throat-plate, a cutting member movably mounted on the clamp plate and provided with a cutting edge, and means operative at the end of the stitching operation to move said cutting member so as to carry its cutting edge first across the throat-plate and then over the shearing edge whereby said cutting edge will draw out a length of stay-cord from the throat-plate and then shear said cord close to the work.

5. In a sewing machine, the combination 55 with a clamp plate on which the work is clamped and provided with a sewing opening, of stitch-forming mechanism including a throat-plate, a shearing block adjustably mounted on the clamp plate and provided with a shearing edge situated at one side of the throat plate, a cutting member movably mounted on the upper side of the clamp plate and situated between the latter and the work, said cutting member having a cutting edge movable across the throat plate and toward and from the shearing edge, and means to actuate said cutting member.

6. In a sewing machine, the combination 60 with stitch forming mechanism including a throat plate on which the work is supported, means for moving the clamp plate and stitch-forming mechanism relative to each other, said clamp plate having a shearing edge on its upper face on one side of the throat plate, a cutting member on the upper side of the clamp plate and provided with a cutting edge movable across and beyond both the throat plate and the shearing edge and co-operating with the throat plate to draw off a length of thread and with the shearing edge to cut the thread between the work and the clamp plate, and devices operating independently of the relative movement between the work clamp and stitch-forming mechanism to actuate the cutter.

7. In a sewing machine, the combination 65 with stitch-forming mechanism, of a clamp plate on which the work is clamped, said clamp having a sewing opening, a shearing block provided with a shearing edge secured to the clamp plate, a cutting member pivoted to the clamp plate and operating to cut the thread between the work and the clamp plate a cam member for moving the clamp plate relative to the stitch-forming mechanism, an actuating member rigid with the cam member and means actuated thereby to operate the cutting member at the end of the stitching operation.

8. In a sewing machine, the combination with stitch-forming mechanism, of a clamp plate on which the work is clamped, said clamp plate having a sewing opening, a shearing block provided with a shearing edge secured to the clamp plate, a cutting member pivoted to the clamp plate and operating to cut the thread between the work and the clamp plate, a cam member for moving the clamp plate relative to the stitch-forming mechanism and lever devices actuated thereby for giving movement to the cutting member. 10

In testimony whereof, I have signed my name to this specification.

JOHN KIEWICZ.
